UNITED STATES PATENT OFFICE.

WILLIAM THOMAS COOPER, OF NASHVILLE, TENNESSEE.

DUMPING-CAR.

SPECIFICATION forming part of Letters Patent No. 449,524, dated March 31, 1891.

Application filed October 18, 1890. Serial No. 368,510. (No model.)

To all whom it may concern:

Be it known that I, WILLIAM THOMAS COOPER, of Nashville, in the county of Davidson and State of Tennessee, have invented certain new 5 and useful Improvements in Dumping-Cars; and I do hereby declare that the following is a full, clear, and exact description of the invention, which will enable others skilled in the art to which it appertains to make and use the 10 same, reference being had to the accompanying drawings, and to the letters of reference marked thereon, which form part of this specification.

This invention relates to certain improvements in dumping-cars.

The object of the invention is to provide an automatic dumping-car exceedingly cheap, simple, and durable in construction, composed of a minimum number of strong parts, and 20 which will automatically dump its load and will automatically close its swinging bottom after dumping the load to be in readiness for the reception of another load. These objects are accomplished by and this invention consists in certain novel features of construction and in combinations of parts more fully described hereinafter, and particularly pointed 25 out in the claims.

Referring to the accompanying drawings, 30 Figure 1 is a perspective of a track and car thereon embodying this invention. Fig. 2 is a vertical longitudinal section of the car, the track or trestle being shown. Fig. 3 is an end view of the car, the track or trestle being 35 shown. Fig. 4 is a detail perspective view of the trigger for upholding the bottom door or doors of the car. Fig. 5 is a detail perspective view of one of the swinging bottom doors, showing its journals and closing-arm. Fig. 40 6 is a detail perspective view of the trip and its frame for operating the trigger to open the bottom door or doors. Fig. 7 is a detail perspective view of the trip for closing the bottom doors and its frame.

45 In the drawings, the reference-letter *a* indicates the elevated track or trestle above the place where it is desired the cars traveling on said track shall dump their contents. The cars *b* are of any ordinary construction to 50 hold the quantity of material desired, and their bottoms are composed of one or more vertically-swinging wings or doors *c*. (Two

are shown in the present instance.) Each door *c* is provided at one longitudinal edge with the end journals or gudgeons *d*, strongly 55 mounted in the car-frame, so that the door can swing up to close the bottom of the car or can swing down by reason of the weight of the material in the car to dump the same. Each door is held in its raised and closed position by suitable means, such as a swinging gravity (or other) trigger *e* near its upper end, pivoted at *e'* to a cross-beam *f* on one side of the opening in the bottom of the car to allow the trigger to rock vertically. When 60 the door is swung up, its free end strikes against the edge of the upper end of the trigger and pushes it back out of the way to allow the door to pass, and when the door has passed the trigger swings back under the edge 70 of the door and holds the same raised. The lower end of the rod composing this trigger is extended down, and by reason of its weight normally holds the upper locking end of said trigger in position to uphold the bottom door. 75 One journal *d* of each swinging bottom door is extended out through the side of the car-frame and provided with a downwardly-extending crank-arm *d'*, inclined rearwardly at 80 a suitable angle.

Over the spot where the contents of the car are to be dumped suitable mechanism is located to operate the trigger to drop the bottom door, such as a pivoted trip or dog *g*, located on the track. This dog is supported in a suitable frame *h*, centrally secured to a cross-tie or other support. The frame *h* has a pair of downwardly-extending legs. (See Fig. 6.) The pivoted trip is provided with cross bars or heads *g'* at its opposite ends and is pivoted at 90 *g''* within its length to said frame, so that its upper end will extend upwardly a suitable distance above the track and its lower end will be opposite said legs of the frame. This trip is arranged so that it can swing into a 95 horizontal position when struck by an object moving in one direction on the track, but when struck by an object moving in the opposite direction the lower cross-piece *g'* will strike against said legs of the frame *h* and hold the trip rigid in the vertical position. 100 Suitable mechanism is employed for closing the bottom doors, such as a similar tripping device *i*, located on the outer side of the

track; but it is provided with a flat upper end or head *j* to engage the crank-arms *d* of the swinging bottom doors to close the same. This trip is arranged so that its upper end will 5 swing in the opposite direction to the trip *g*.

When a car has been loaded, it passes down the track to the dumping ground or spot, and upon arriving over the dumping-spot the upper end of the trip *g* engages the lower end of 10 the trigger *e* and forces the lower end thereof rearwardly and the locking or door-supporting end thereof forwardly from beneath the swinging door. Thereupon the weight of the material on the door causes it to swing down, 15 thereby dumping the contents of the car. If there are several doors, they are consecutively opened, as described. When the doors are open, the crank - closing arms thereof are swung down and forwardly. As the car is 20 started on the return-trip, the lower end of the trigger *e* strikes against the upper end of trip *g* and swings the same down into horizontal position to allow the trigger to pass the trip. The closing-arm of the open bottom door then 25 engages the upper end *j* of the trip *i* on the outer side of the track. This causes said arm to swing back to incline toward the front end of the car, thereby swinging up the door, which is caught by the trigger *e*. When the 30 trip *i* is engaged by the closing-arm when moving in the other direction, the trip is swung into its horizontal position and allows the arm to pass.

It is evident that various changes might be 35 made in the form and arrangement of the parts described without departing from the spirit and scope of my invention. Hence I do not wish to confine myself to the precise construction herein set forth.

40 What I claim is—

1. A dumping-car having the vertically swinging bottom door pivoted at one transverse edge, the vertical trigger beneath the car, pivoted near its upper end to a beam thereof, with its lower end projecting below the car to engage a trip on the track to swing the trigger, the upper end of said trip being arranged to swing beneath the free edge of the door and uphold the same, as set forth.

45 2. A dumping-car having a swinging bottom door and a pivoted trigger to hold the same closed and raised, said trigger swinging

in a plane parallel with the direction of movement of the car, in combination with a vertical swinging trip on the track to engage 55 and operate said trigger to release the door and allow the contents of the car to discharge.

3. A dumping-car having a swinging bottom door, a trigger to hold the door closed, and an arm connected with the door to close 60 the same, in combination with mechanism, substantially as described, located beside the track, to operate said arm to close the door.

4. A dumping-car having a swinging bottom door provided with lateral journals, a lateral closing-arm rigid with one of said journals, and a trigger to hold said door closed, 65 substantially as described.

5. A dumping-car having a swinging trigger to hold its bottom door closed, in combination with a trip on the track to operate said trigger to release the door, said trip consisting of a swinging arm pivotally mounted on a frame secured to a support free to move in one direction and a stop to limit its movements in the other direction. 75

6. In a dumping-car, the combination of the swinging bottom door provided with the lateral journals, one of the said journals being extended through the side of the car and bent 80 laterally and downwardly at the exterior thereof to form a closing-arm, with a swinging trigger to uphold said door, substantially as described.

7. The combination, with a support, of a frame secured thereto having downwardly extending legs and a bend at its upper end, and the vertical trip-arm pivotally mounted between its ends in said bend and provided with a head, so that its swing in one direction 90 will be limited, as set forth.

8. The combination of a car having a swinging bottom door, a swinging trigger to movably uphold the same, and a swinging trip on the track to engage and operate said trigger 95 and a stop to limit the swing of said trip in one direction, substantially as described.

In testimony that I claim the foregoing as my own I affix my signature in presence of two witnesses.

WILLIAM THOMAS COOPER.
